UNITED STATES PATENT OFFICE.

WILLIAM J. EICHENBERG, OF TOLEDO, OHIO, ASSIGNOR TO INDUSTRIAL RESEARCH CORPORATION, OF TOLEDO, OHIO, A CORPORATION OF DELAWARE.

DRIVING MECHANISM.

Application filed July 22, 1918, Serial No. 246,137. Renewed September 6, 1923.

This invention relates to a motor drive applicable in the driving mechanism intermediate the motor and internal combustion engine, and has specific adaptation when employed for starting purposes.

The principal object of the invention is to utilize a type of gearing wherein there is a positive drive relationship between the various parts, and wherein the resilient elements are employed without inserting them in the direct line of power transmission.

Another object is to provide means whereby connection and disconnection with the driving gear and the driven element is made in an entirely automatic way.

A further object is to provide means for overcoming the misengagement of the movable parts when starting, thereby preventing breakage.

Further objects, and objects relating to economies of manufacture and details of construction, will definitely appear from the detailed description to follow.

A structure constituting a preferred embodiment of my invention is illustrated in the accompanying drawings, forming a part of this specification, in which:

Figure I shows the driving mechanism partly in section with the elements in disengagement.

Figure II shows a similar view in longitudinal section.

Figure III shows a view of the drive in operative position with parts thereof in section.

Figure IV is a cross-section through the resilient elements of the drive, taken on line IV—IV of Figure II, and,

Figure V is a cross-section taken along the line V—V of Figure III.

Similar reference numerals refer to similar parts throughout the several views, and the sections are taken looking in the direction of the small arrows.

Referring to the numbered parts of the drawing, I have shown a portion of the gear wheel 1, which may take the form of a fly wheel directly connected to the crank shaft of an internal combustion engine. Positioned adjacent the periphery of the gear 1 is an electric motor 2 which is preferably of the series type. The shaft 3 of this motor

extends parallel with, and a short distance from the teeth of the gear wheel, and near its outer end, the shaft is cut with a low pitched thread as indicated at 4 in Figure II.

There is mounted on the motor shaft, adjacent the motor, a sleeve 5, the outer surface of which is threaded. To the inner end of this sleeve is rigidly secured a terminal collar 6 and the outer end of the sleeve is fashioned so as to form two outwardly extending lugs 7 and 8, positioned on opposite sides of the sleeve, and having inner partially flat parallel surfaces and outer surfaces lying in the circumference of a circle. Between the end lugs 7 and 8 and the threaded portion of the sleeve, an annular flange 9 is formed integral with the sleeve for a purpose hereinafter to be described.

Driving relationship between the sleeve and the gear 1 is established by a pinion 10 which has threaded engagement with the sleeve, and is adapted to have axial movement along the sleeve into mesh with the gear 1. The inner ends of the gear teeth are curved as shown at 11, so that ready enmeshment may be made between the pinion and gear teeth. The outer end of the pinion carries an annular flange 12, a part of which is out-turned and thickened to form a counterweight 13. Means are provided for preventing the pinion from traveling inward along the thread from the outer end of the sleeve, unless an appreciable rotational force is applied thereto. This means consists in a pin 14, which has bearing in an aperture formed in the out-turned portion of the counterweight, and the end of which rests on the sleeve intermediate the flange 9 and the wall formed by the termination of the threads. A small stop 15 is formed on this pin, adjacent the sleeve, and a coil spring 16 is interposed on the pin intermediate the stop and the counterweight surface.

The pin is so positioned on the counterweight, that when the pinion begins to screw inwardly on the sleeve, the pin will move into contact with the outer end of one of the threads of the sleeve, so that unless there is considerable rotational force such as would be applied during the starting operation, the pin will fail to ride over the thread,

and the pinion will remain at the outer end of the sleeve.

Driving connection between the shaft and sleeve 5 is made through a plurality of 5 intermovable elements, which in assembled formation, have the appearance of a spool consisting of two conical-shaped end pieces with their conical portions connected by a horizontal portion. For ease in description, I 10 shall describe the portion of this drive at the end of the motor shaft, as the outer part, and the portion of the drive adjacent the outer end of the sleeve, as the middle part. The middle part 17 is mounted adjacent the 15 outer end of the sleeve 5, with its conical surface 18 inclined outwardly. The bearing surface of the middle part 17 is slotted longitudinally at four points equi-distant from each other, along the circumference of the bearing surface, as indicated at 19, Figure 20 IV, and within two oppositely positioned slots the projecting lugs 7 and 8 of the sleeve are adapted to have sliding movement. The outer part 20 has its conical surface 21 inclined inwardly toward the motor, and has 25 threaded engagement with the threaded end portion of the motor shaft. The conical surface of the outer part 20 and the middle part 17 have channels cut in their surfaces at opposite sides, as indicated at 22 and 23, so that the edge walls of these slots lie in parallel planes. Mounted so as to have bearing at their ends in these channelled portions 22 and 23 are blocks 24, the ends of which are 30 cut so as to be parallel with the base walls of the channels. Sliding movement of these blocks along the channels is resisted by a coiled spring 25, which tends to hold the blocks in position at points nearest the motor shaft. The inner end of the outer part 20 is cut to form four teeth 26, so positioned as 35 to mesh with the bearing slots of the middle parts 17, so that there is a positive drive connection between these two parts. Intermediate the flange 9 on the outer end of the sleeve 5 and the middle part 17, is placed 40 a coil spring 27, which tends to move the middle part outwardly from the sleeve. The outer part 20 is prevented from screwing out 45 on the shaft by a terminal nut 28.

In the operation of the driving mechanism, when the motor shaft has rotation as indicated by the curved arrow in Figure II and with the pinion out of engagement with 55 the gear, the pinion begins to screw inwardly along the thread of the sleeve until it has complete enmeshment with the engine gear. At this point, the inner end of the pinion is 60 in contact with the collar 6 on the sleeve, and since it is prevented from further axial movement, the pinion takes up the rotational speed of the sleeve. Inasmuch as the inertia of the gear is considerable, it is impossible 65 that the gear take on immediately the motor speed, and unless means are provided for

absorbing some of the rotational force of the motor shaft, serious breakage is bound to result.

In the mechanism that I have described, when the pinion is prevented from further 70 movement along the axis of the shaft, the outer part 20 of the drive, which is held from rotation by virtue of its direct connection to the pinion and engine gear begins, through the rotation of the shaft, to screw 75 inwardly along the shaft, the ends of the block 24 riding along the inclined channels 22 and 23, against the resilient force of the coiled spring 25, as clearly indicated in Figure III of the drawings. This sliding 80 movement of the blocks continues until the inertia of the gear has been overcome, and the gear takes on a rotational speed having a constant ratio to that of the motor shaft. At this point, the engine is designed to start 85 up under its own power, when the greatly increased speed of the engine gear screws the pinion back out of mesh therewith, until the pin 14 in the counterweight of the pinion 90 rides over the outer thread of the sleeve. 95

In case the pinion fails to mesh with the teeth of the gear 1, its teeth abutting with the gear teeth, the sleeve will slide outwardly along the motor shaft against the compression of the spring 27, thereby permitting a 95 slight rotational movement of the pinion, sufficient to allow proper enmeshment thereof with the gear.

From the foregoing description, it is apparent that the sole function of the spring 100 25 is to absorb the jar incident upon the sudden application of force to the engine gear, and that the spring does not form an element in the direct line of power transmission, intermediate the motor shaft and gear. 105 It should also be apparent that connection of the pinion and gear and disconnection of these parts is made in an entirely automatic way, the movements being dependent upon the variations in the relative speeds of the 110 movable parts. The position of the spring upon the drive enables replacement to be readily made and the type of spring employed permits of ease in manufacturing, 115 assembly and cheapness in construction. 120

I am aware that the particular embodiment of my invention, as herein shown and described, is susceptible of considerable variation without departing from the spirit thereof, and, therefore, I desire to claim the 125 same broadly, as well as specifically, as indicated by the appended claims.

Having thus described my invention, what I claim as new and desire to secure by Letters Patent, is:

1. A motor drive for internal combustion engines, comprising in combination an engine gear; a starter shaft, one end of which is threaded; an externally threaded sleeve on said shaft; a middle driving part on the 120

shaft having a slidable connection with the sleeve; an outer driving part having threaded engagement with the outer end of the shaft and having a slidable connection with the said middle part, said outer and middle parts having longitudinal channels cut on adjacent sides forming guide ways; blocks having sliding movement in said channels; resilient means tending to oppose movement of the blocks; and a pinion axially movable on the sleeve and adapted to make automatic engagement and disengagement with said gear.

2. A motor drive for internal combustion engines, comprising in combination with an engine gear, a starter shaft, one end of which is threaded, an externally threaded sleeve on said shaft, a driving part on the shaft having driving connection with the sleeve, a second driving part having threaded engagement with the outer end of the shaft, the adjacent faces of said driving parts being conical, a slidable connection between said parts, a spiral band spring interposed between said driving parts and tending to force them apart, and an internally threaded pinion mounted upon said sleeve and adapted to engage said gear.

3. In combination with the toothed flywheel of an internal combustion engine, a pinion adapted to mesh therewith, a starter shaft threaded at one end and a driving connection between said shaft and pinion including a driving member loose on the shaft, a second driving member having a threaded connection with said shaft, the adjacent faces of said middle and second driving members being conical, a connecting member between said driving members, adapted to have a slidable bearing on the conical faces thereof, and a spiral band spring interposed between said driving members.

4. In a drive mechanism, the combination of a driveshaft threaded at one end; a nut in threaded engagement with the threaded end of the shaft; an externally threaded sleeve loosely mounted on the shaft; a driving member mounted on the shaft between the nut and sleeve; and a radially movable connecting element between said driving member and nut.

5. In a drive mechanism, the combination of a drive shaft threaded at one end; a nut in threaded engagement with the threaded end of the shaft; an externally threaded sleeve loosely mounted on the shaft; a driving member mounted on the shaft between the nut and sleeve; a radially movable connecting element between said driving mem-

ber and nut and resilient means tending to resist the radial movement of said connecting element.

6. In a drive mechanism, the combination of a drive shaft threaded at one end; a nut in threaded engagement with the threaded end of the shaft; an externally threaded sleeve loosely mounted on the shaft; a driving member mounted on the shaft between the nut and sleeve; and a rigid connecting element between the driving member and nut, movable relative to both said member and nut.

7. In a drive mechanism for engines, the combination of an engine gear; a starter shaft; an externally threaded sleeve mounted on the shaft; a pinion on said sleeve having threaded engagement therewith and adapted to have axial movement into engagement with said gear; a second sleeve on said shaft having a sliding engagement with said first named sleeve; resilient means tending to force said sleeves apart; and a third sleeve on the shaft having means tending to force said second named sleeve toward said first named sleeve when the engine is being started.

8. In a drive mechanism for engines, the combination of an engine gear; a starter shaft; an externally threaded sleeve mounted on the shaft; a pinion on said sleeve having threaded engagement therewith and adapted to have axial movement into engagement with said gear; a second sleeve on said shaft having a sliding engagement with said first named sleeve; a spring mounted between adjacent ends of said sleeves and tending to force them apart; and a third sleeve on the shaft having means tending to force said second named sleeve toward said first named sleeve when the resistance of the engine to rotation hinders relative movement between the shaft and first named sleeve.

9. In a drive mechanism for engines, the combination of an engine gear; a starter shaft; an externally threaded sleeve mounted on the shaft; a pinion on said sleeve having threaded engagement therewith and adapted to have axial movement into engagement with said gear; a second sleeve on said shaft having a sliding engagement with said first named sleeve; resilient means tending to force said sleeves apart; and means tending to force said second named sleeve toward said first named sleeve when the free rotation of the latter is hindered.

In testimony whereof, I affix my signature.

WILLIAM J. EICHENBERG.
